UNITED STATES PATENT OFFICE.

ANGUS McCALLUM, OF PONTIAC, MICHIGAN.

ROAD-SCRAPER.

1,112,713.

Specification of Letters Patent.

Patented Oct. 6, 1914.

Application filed December 13, 1913. Serial No. 806,377.

To all whom it may concern:

Be it known that I, ANGUS McCALLUM, a citizen of the United States, residing at Pontiac, county of Oakland, State of Michigan, have invented a certain new and useful Improvement in Road-Scrapers, and declare the following to be a full, clear, and exact description of the same, such as will enable others skilled in the art to which it pertains to make and use the same, reference being had to the accompanying drawings, which form a part of this specification.

This invention relates to machines for evening roads and has for its object a machine which is adapted to perform its work in a good and efficient manner by reason of the particular disposition of the blades. The middle blade is adjustable vertically and the depth of its cut may be regulated by the swinging of the rear blade. This will more fully appear in the specification.

In the drawings:—Figure 1, is a top plan view of the scrapers and the frame. Fig. 2, is a side view of the same. Fig. 3, is a detail of the control device for regulating the adjustment of the rear blade. Fig. 4, is a detail of the fastening of the middle blade to the frame. Fig. 5, is a detail of that part of the chain omitted from the right of Fig. 1.

30 A pair of parallel side bars *a* are fastened together by the braces *b*. A front blade *c* is diagonally set upon the front ends of the side bars *a*—*a*. The middle blade *d* is set perpendicularly with respect to the side bars 35 to which it is attached by means of the hangers *e*. The middle blades are slotted as at *f* so that they may be adjusted slightly vertically with respect to the hangers by loosening the bolt *g*. The middle blade or 40 scraper is concave on its forward side, the concavity being of uniform character at the top and bottom so that the scraper can be inverted and used with the top edge at the bottom when desirable. The rear blade *h* has its 45 edge *i* turned rearwardly so as to ride over the road already cut by the middle scraper. The rear blade is fastened to the hangers *j* that are pivoted to the side bars. The lever *k* is also fastened to the rear blade and 50 swings across the face of a perforated segment *l*. A locking pawl *m* is pivoted so as to swing transversely of the lever and has a point adapted to drop into the perforations in the segment *l* so that the blade *h* may be

held in different inclinations. A chain *n* is 55 attached to each end of the side bars at the front and may be connected with any suitable means for pulling.

The obliquely set front blade *c* is intended to throw to the sides of the machine any 60 surplus accumulations of dirt and other matter along the surface of the road. It also acts as a support for the front of the frame. The middle blade or scraper *d* is intended to cut into the surface of the road to cut down 65 the high portions and to fill up the low portions. Its perpendicular disposition with respect to the frame accomplishes this work better than would be the case if it were obliquely set. It carries the dirt along in 70 front of it and allows it to drop into low places.

By dropping the lever *m* the blade *h* may be inclined with respect to the ground and the more the lever is dropped the deeper the 75 middle blade *d* will cut. The turned-over edge *i* of the blade *h* acts to smooth off the portions of the road that have been cut by the scraper and portions of the road that have been filled in by the same. It, therefore, 80 performs a double function as a control for the scraper and as an evener.

What I claim is:—

1. A machine for evening roads, having in combination, a frame, a front blade that contacts the ground and that is carried by the frame, a middle blade carried by the frame, a rear blade or drag that is arranged to ride over the ground without cutting the same, the said rear blade being pivoted near its 85 upper edge to the frame, and a lever pivotally mounted upon the frame and connected with the rear blade so as to tip only the rear blade when operated, the said rear blade being set with respect to the other two blades 90 so that the tipping of the rear blade raises or lowers the frame upon the front blade as a fulcrum, thereby regulating the cut of the middle blade.

2. A machine for evening roads, having in 100 combination, a frame, a front blade that contacts the ground and that is carried by the frame, a middle blade acting as a cutting blade and carried by the frame, a rear blade arranged to slide over the ground without 105 cutting into the same, hangers attached to the rear blade and pivoted to the frame so as to carry the point of pivoting above the

upper edge of the rear blade, and a lever attached to one of the hangers and fixable in various angular positions with respect to the frame upon which it is pivoted, said rear 5 blade being arranged with respect to the middle and front blade so that tipping of the rear blade by operating the lever raises or lowers the frame on the front blade as a

fulcrum, so as to regulate the cut of the middle blade.

In testimony whereof, I sign this specification in the presence of two witnesses.

ANGUS McCALLUM.
